Attorney.

UNITED STATES PATENT OFFICE.

DAVID FOX, OF NEW YORK, N. Y.

WINTER CAP.

SPECIFICATION forming part of Letters Patent No. 239,757, dated April 5, 1881.

Application filed January 5, 1881. (Model.)

To all whom it may concern:

Be it known that I, DAVID FOX, of the city, county, and State of New York, have invented a new and useful Improvement in Winter Caps; and I do hereby declare that the following is a full, clear, and exact description of the same, reference being had to the accompanying drawings making part of this specification.

10 This invention is in the nature of an improvement in caps; and the invention consists in a cap constructed with a cape or ear and neck protector having its ends united in front by an elastic connection, whereby it may be 15 drawn over the visor of the cap, if desired, and also having the upper edge of the protector fastened to the body of the cap above the lower edge of the cap-body; and the invention still further consists in securing to the protector, at or near the fold of the same, ears 20 whereby the protector may be drawn or folded up with facility, all of which is more particularly described in the following specification, and shown in the accompanying drawings, 25 wherein—

Figure 1 represents a perspective view of my cap with the protector raised; Fig. 2, a perspective view of same with protector pulled down; Figs. 3 and 4, detail front and edge 30 views of forward ends of protector or cape, showing method of uniting same by elastic strip; Fig. 5, plan view of protector-strip; and Fig. 6, perspective view of my cap with modified form of ears for cape.

35 Similar letters of reference indicate like parts in several figures.

As is well known, caps for winter wear are generally constructed with capes or protectors which may be drawn down below the cap-body for the purpose of covering the ears and neck of the wearer in cold weather, and a variety of such caps have heretofore been made and used, some of which being provided with protectors which swing and slide on pivots and 40 an intermediate lining of muslin; others with protectors which turn over and down, covering the ears and neck, and still others in which the protector folds down and upon the cap-body, each of these being more or less objectionable. The present invention is intended 45 as an improvement on them, more particularly

of that class of cap whose protector folds up and down on the cap-body.

To that end I construct my cap-body A of any suitable shape and size, and of any suitable material, and with or without a visor. To the rear part of this cap-body and some distance up from its lower edge (see Figs. 1 and 2) is secured the upper edge of a cape or protector, B, the protector thence continuing with 55 diminished width to the front of the cap, where its two ends are united by an elastic, C, which secures the two ends to each other. To the protector B, at or near its place of folding a, and at its rear part, are secured ears D. These 60 ears may be so attached as to be entirely concealed when the protector is drawn up, if desired, or otherwise.

Now, my cap, constructed substantially as described above, is operated as follows: The 70 cap being upon the head of the wearer, with the protector up and encircling the body of the cap, as shown in Figs. 1 and 6, it remains in position by reason of its close contact with the cap-body, presenting an ornamental appearance.

When it is desired to use the cape or protector for the purpose of protecting the ears and neck of the wearer, the protector, by its lower edge, b, is drawn downward until it 80 snugly and fully covers the ears of the wearer and his neck. (See Fig. 2.) As the protector is drawn down (if the cap is provided with a visor) the elastic strip C permits the protector at its ends to spread apart, and thereby allow 85 the protector at its sides to come well down over the ears of the wearer, or, if desired, the ends of the protector or its elastic fastening C will yield sufficiently, so as to permit the ends of the protector being drawn down and over 90 the visor and onto the face of the wearer. This adjustment of the protector, whether entirely over the visor or otherwise, insures the protection of the front part of the wearer's ears, by allowing the sides of the protector to fall sufficiently down for that purpose, the movement of the protector being more of the vertical up-and-down movement than that of a swinging one, as in the case of pivotal buttons or similar attachment to sides or ends of the protector. 95 The protector being drawn downward, as just described, it is restored to its position of en-

circling the cap by the ears D, which, being located at or near the fold *a* of the protector, enables the wearer, by pulling the same upward, to fold the protector up on the cap-body, as is shown in Figs. 1 and 6.

By attaching the upper edge of the protector to the cap-body some little distance from its lower edge not only is a saving of material effected in the width of the protector, but less material is required to fold up when the protector is adjusted upward. Therefore the protector can the more readily be adjusted than would be the case if the protector were attached to the lower edge of the cap-body. Still another advantage is derived by uniting the front ends of the protector by an elastic fastening, which is that the cape or protector will yield, and therefore not bind the head of the wearer uncomfortably, as is the case with caps having protectors otherwise united.

The sole purpose of the ears D hereinbefore described is that of handles located at proper

places on the protector, which the wearer can grasp and therewith fold up the protector when not in use around the body of the cap.

25

Having thus described my invention, what I claim as new, and desire to secure by Letters Patent, is—

1. A cap with folding ear and neck protector secured at its upper edge to the rear portion of the cap and above the lower edge of the cap-body, the front ends of the protector being united to each other by an elastic strip, substantially as described.

2. In a cap with a folding ear and neck protector, ears D, fastened to the rear part of the protector, at or near its place of folding, whereby the protector may be folded up and around the body of the cap, as shown and described.

DAVID FOX.
